INVENTOR.

INVENTOR.
FRANK STONER.
Edward R. Alexander
Attorney

UNITED STATES PATENT OFFICE.

FRANK STONEER, OF LAKWOOD, OHIO, ASSIGNOR TO THE BAKER-RAULANG COMPANY, OF CLEVELAND, OHIO, A CORPORATION OF OHIO.

RECEPTACLE.

Application filed August 26, 1922. Serial No. 584,509.

This invention relates to receptacles, more particularly to that type wherein the receptacle is normally disposed in an opening in a wall or other support and flush with its outer surface but is movable relative thereto to permit access to its interior.

One object of the invention is to provide a receptacle of this character that is relatively simple in construction.

Another object of the invention is to construct an improved receptacle wherein the means which operate the movable section of the receptacle also serves to arrest the section at a predetermined open position.

Other objects of the invention will be apparent to those skilled in the art to which my invention relates from the following description taken in connection with the accompanying drawings, wherein

Fig. 1 is an elevation of an automobile having associated with it a receptacle embodying my invention, parts of the automobile being broken away to show the receptacle in position.

Fig. 2 is a fragmentary elevational view showing the receptacle when in closed position.

Fig. 3 is a sectional view on the line 5—5 of Fig. 2, but showing the receptacle in open position.

Fig. 4 is a sectional view on the line 5—5 of Fig. 2, but illustrating the operation of attaching the operating device to the holder or detaching it therefrom.

Fig. 5 is a sectional view on the line 5—5 of Fig. 2, but showing the holder disconnected from the operating device and moved to full open position.

Fig. 6 is a front view of the parts as shown in Fig. 5, on the line 6—6, showing the operating device moved to an in-operative position.

Fig. 7 is a fragmentary sectional view on the line 5—5 of Fig. 2 illustrating the operation of releasing the holder.

Fig. 8 is a section on the line 8—8 of Fig. 5.

In the drawings, 1 indicates a vehicle of any desired construction, for example, an automobile having a sedan type of body. 2 indicates as an entirety a receptacle, any number of which may be provided in the vehicle. In the accompanying drawings I have shown two receptacles 2, one in the side wall of the vehicle adjacent its rear seat and

the other in the back of the front seat, which wall and back form suitable supports or mountings for receptacles embodying my invention. It will be obvious that they may be arranged in other positions and as many provided as conditions may make it necessary or desirable.

The receptacle 2 preferably comprises a casing 3 and a holder 4, which are respectively shaped so that the holder may fit within the casing. The casing may be and preferably is fitted to a recess 1' formed in the vehicle body or positioned in a space or opening between its structural members. By this arrangement and construction, the outer wall of the receptacle or its holder, when the latter is in closed position, is flush with the surrounding wall or surface of the vehicle body.

The casing 3 comprises a bottom 5, side walls, 6, 6, a top wall 7 and a bottom wall 8. The top and bottom walls 7, 8, and the side walls 6 are preferably provided with flanges 9, which extend outwardly and thus may fit over the interior lining of the vehicle body to protect it as well as to improve the appearance of the body. The casing 3 may be secured in position by a plurality of screws 10, extending through suitable openings formed in the side walls 6. The holder 4 is constructed to provide a face plate 4^a and one or more compartments 4^b of a size and shape best adapted to contain articles desired for use while riding. The face plate 4^a is preferably of a size to fit within the side walls 6 and top and bottom walls so that it will be disposed in the plane of the flanges 9 and the surface of the support 1 when the holder 4 is closed. The compartments 4^b are preferably arranged to permit access to their interiors from their upper ends when the holder is hinged along its lower side edge as shown in the drawings.

The holder 4 is movably connected to the casing 3 so that it may be moved relative thereto to permit ready access to the compartments 4^b. For this purpose the holder is hinged along one edge or side, preferably its lower edge or side, by means of hinges 4'. When so constructed, the upper end of the holder swings outwardly as shown in Fig. 3.

11 indicates an entirety means for locking the holder in its closed or normal position. Of these means, 12, 12', indicate a pair of elements carried by the casing 3 and 110

holder 4, respectively, and co-acting to engage each other to lock the holder in closed position, one of said elements being movable relative to the other so that it may be disengaged therefrom when it is desired to open the receptacle. The stationary locking element, indicated at 12, is preferably secured to the holder 4 and the other element 12' is carried by the casing 3. The element 12 may 10 comprise a section of metal secured in any well known manner to the inner side of the face plate 4^a, its free end being shaped to form a hook 13. The element 12' is pivotally mounted on the inner face of the top 15 wall 7 so that its free end, which is shaped to provide a hook 14, may engage with the hook 13 and be disengaged therefrom in the manner to be later set forth. The locking element 12' is normally maintained in locking 20 position by a spring 15 which is preferably coiled around the pivot for the locking element, and acts thereon in a well known manner to operate the locking element 12' in one direction and to resist its movement 25 in the opposite direction, this construction permitting the locking elements 12, 12', to automatically engage each other when the holder is moved from its open position to its closed position. The locking element 12' 30 is provided with a tail piece 16 which is preferably operated by a plunger 17. The plunger 17 is guided in a pair of openings 18, 19, the former being formed in the adjacent flange 9 and the latter being formed 35 in a lip 20 struck-up from the metal constituting the upper wall 7, such struck-up portion providing an opening 21 in the wall 7 through which the tail piece extends so that its free end may be disposed in the 40 path of movement of the plunger 17. The spring 15 preferably acts through the locking element 12' and tail piece 16 to push the plunger 17 outwardly and normally maintain it in the position shown in Figs. 45 3, 4, and 5; the plunger being provided with a head 22 engaging the lip 20 to limit its outward movement.

23 indicates a device disposed within the casing 3 and acting on the holder 4 to push it outwardly about its hinged connection with the casing 3. The device 23 preferably comprises a strip or plate formed from resilient metal. The device 23 is connected at its lower end, as indicated at 24, to the inner face of the bottom 5 and is bent upwardly and outwardly, so that when the holder 4 is moved to its closed position, it will compress the free end of the device 23 and thus put it under tension. As a result of 50 this construction and operation, the device 23 will act on the holder and swing it outwardly, upon the release of the locking means 11. The connection 24 for the operating device 23 is preferably of a pivotal character so that it may be moved about its

pivot to the position shown in Fig. 6 for a purpose to be later set forth. Near its outer end, the operating device 23 is formed with an elongated opening or slot 25 arranged to receive a member 26 such as a 70 pin or stud, carried by the inner wall of the holder 4. During movement of the holder 4 outwardly the stud moves endwise of the slot 25 until it engages the outer end wall thereof. As the pin or stud is carried 75 by the holder, the end wall of the slot will limit or stop the outward movement of the holder at a predetermined position, see Fig. 3. The outer end of the pin or stud 26 is preferably provided with a head or flange 80 26^a which engages the remote surface of the operating device 23 at either side of the slot 25 and operates to connect the pin or stud to the operating device 23, thereby preventing the disconnection of the stud from the 85 end wall of the slot when the holder is arrested thereby. Intermediate its ends, the slot 25 is enlarged, as shown at 26^b, see Fig. 6, so that the head or flange of the pin or stud can be positioned on the remote side 90 of the operating device or removed therefrom. To permit of either of these operations, the holder 4 is first moved to an intermediate position, that is, that position in which the pin or stud 26 is opposite or in 95 alignment with the enlarged portion 26^b, and then by means of a pencil or other suitable device the operating device 23 is held against outward movement (see Fig. 4), while the holder is permitted to swing about 100 its hinged connection with the casing 3 until the pin or stud is free of the walls of the slot 25. This construction and arrangement permits the holder 4 to be positioned as shown in Fig. 5. When in such position the 105 casing 3 may be secured in the opening or recess in the vehicle body wall. Therefore it will be seen that the receptacle can be completely manufactured and assembled 110 ready for assembly in the vehicle body. This construction also permits the holder 4 to be disconnected from the operating device at will, for example, when it is desired to swing the holder to its full open position. When the holder is to be thus operated, the 115 operating device 23 may be swung about its pivot 24 to the position shown in Fig. 6.

27 indicates a spring preferably coiled around the pivot pin for the hinge 4' and normally operating to move the holder outwardly and maintain it in open position. I have shown in the drawings two springs 27, although one may be sufficient. The springs 27 are supplemental to the operating device 23. Where the holder 4 is relatively 120 small and but few articles are to be kept therein the spring or springs 27 may be omitted.

It will be understood that my invention is not, in its broader aspects, limited to a re- 125 130

ceptacle construction in which a casing, such as indicated at 3 in the drawings, is required, since the holder 4, elements of the locking means and the operating devices 5 may be mounted on the wall or walls forming the recess 1' in the support 1.

To those skilled in the art on making devices of the character herein described many alterations and widely differing embodiments and applications of the invention 10 will suggest themselves without departing from the spirit and scope thereof. My disclosures and the description herein are purely illustrative and are not intended to 15 be in any sense limiting.

What I claim is:

1. In a construction of the class described, the combination with a support having a recess, of a holder movably connected to said 20 support so that it may lie within said recess therein substantially flush with the surface of said support and be moved outwardly to permit access to its interior, a device connected to said support and normally 25 acting on said holder to push it outwardly, and a connection between said device and said holder serving to limit the outward movement of the latter, the said connection between said device and said holder being 30 detachable.

2. In a construction of the class described, the combination with a support having a recess, of a holder movably connected to said support so that it may lie within said recess substantially flush with the surface of 35 said support and be moved outwardly to permit access to its interior, a device connected to said support and normally acting on said holder to push it outwardly, a connection between said device and said holder serving to limit the outward movement of the latter, and means supplemental to said device and co-operating therewith to move the holder outwardly.

45 3. In a construction of the class described, the combination with a support having a recess, of a holder movably connected to said support so that it may lie within said recess therein substantially flush with the outer surface of said support and be moved outwardly to permit access to its interior, a resilient plate pivotally connected at one end to said support and normally acting on said holder to push it outwardly, and separable means carried by said plate and holder arranged to limit the outward movement of the latter at a predetermined position.

50 4. In a construction of the class described, the combination with a support having a recess, of a holder movably connected to said support so that it may lie within said recess therein substantially flush with the surface of said support and be moved outwardly to permit access to its interior, a

resilient plate connected to said support at one end and normally acting on said holder to push it outwardly, said plate being formed with an elongated slot, and a member carried by said holder and engaging the outer end wall of said slot to limit the outward movement of the holder.

5. In a construction of the class described, the combination with a support having a recess, of a holder movably connected to said support so that it may lie within said recess therein substantially flush with the surface of said support and be moved outwardly to permit access to its interior, a resilient plate connected to said support at 75 one end and normally acting on said holder to push it outwardly, said plate being formed with an elongated slot, and a member carried by said holder and engaging the outer end wall of said slot to limit the outward movement of the holder, said slot having an enlarged portion to permit the member to be connected and disconnected from said plate.

6. In a receptacle, the combination of a 80 casing, a holder hinged along one end to said casing so that it may lie therewithin substantially flush with the outer end walls thereof and be moved outwardly relative to said casing to permit access to its interior, a resilient plate connected to said casing at 85 one end and normally acting on said holder to push it outwardly, said plate being formed with an elongated slot, and a flanged element carried by said holder and extending through the slot so that the flange thereof will engage the remote surface of said plate, whereby said element will engage the end wall of the slot to limit the outward movement of the holder and the flange will 90 prevent disconnection of said element from said plate.

7. In a receptacle, the combination of a 95 casing adapted to be mounted in a recess formed in a support, a holder hinged along one end to said casing so that it may lie therewithin substantially flush with the surface of the support and be moved outwardly to permit access to its interior, a resilient plate connected to said casing at 100 one end and normally acting on said holder to push it outwardly, said plate being formed with an elongated slot, and a flanged element carried by said holder and extending through the slot so that the flange thereof will engage the remote surface of said plate, whereby said element will engage the end wall of the slot to limit the outward movement of the holder and the flange will 105 prevent disconnection of said element from said plate.

8. In a construction of the class described,

- the combination with a support having a recess, of a holder movably connected to said support so that it may lie within the recess therein substantially flush with the outer surface of said support and be moved outwardly to permit access to its interior, a resilient plate pivotally connected at one end to said support and normally acting on said holder to push it outwardly, and detachable means carried by said plate and holder arranged to limit the outward movement of the latter at a predetermined position.
9. In a construction of the class described, the combination of a support having a recess, a holder within said recess and movably connected to said support along one edge, whereby it may be moved outwardly, a resilient device connected to said support and acting on said holder to move it outwardly, and a detachable connection between said device and said holder serving to limit the outward movement of the latter, said device having a portion which is exposed when the holder is moved outwardly.
10. In a construction of the class described, the combination of a support having a recess, a holder within said recess and movably connected to said support along one edge, whereby it may be moved outwardly,
11. In a construction of the class described, the combination of a support having a recess, a holder within said recess and movably connected to said support along one edge, whereby it may be moved outwardly, and means normally acting to move said holder outwardly and for limiting its movement at a predetermined position, said means including a device interposed between said holder and said support, one end of said device being connected to said support and its other end having sliding engagement with said holder and formed with an elongated slot, and an element carried by the holder and projecting through said slot to engage the end wall thereof to limit its outward movement.
12. In a construction of the class described, the combination of a support having a recess, a holder within said recess and movably connected to said support along one edge, whereby it may be moved outwardly, and means normally acting to move said holder outwardly and for limiting its movement at a predetermined position, said means including a device interposed between said holder and said support, one end of said device being connected to said support and its other end having sliding engagement with said holder and formed with an elongated slot, and an element carried by the holder and projecting through said slot to engage the end wall thereof to limit its outward movement.
13. In testimony whereof, I have hereunto subscribed my name.

FRANK STONER.
